PULL FOR A HANDBAG

Etienne Aigner, New York, N.Y., assignor to Villager Industries, Inc., a corporation of Delaware

Filed Sept. 18, 1968, Ser. No. 13,584

Term of patent 14 years

Int. Cl. D8—03

U.S. Cl. D8—159

FIG-4

FIG-3

FIG. 1 is a front elevational view of a pull for a handbag showing my new design;

FIG. 2 is a rear elevational view thereof;

FIG. 3 is a side elevational view; and

FIG. 4 is a top plan view thereof.

The dominant features of my design reside in the portions shown in solid lines, a trademark being shown in broken lines.

I claim:

The ornamental design for a pull for a handbag, substantially as shown and described.
